FURNACE

James C. Woodson, Cleveland, Ohio, assignor to
Lee Wilson, Cleveland, Ohio

Application April 17, 1936, Serial No. 74,958

11 Claims. (Cl. 266—5)

My invention relates to a furnace and, more particularly, to a furnace of the general type described and claimed in United States Patent to Wilson No. 1,952,402.

5 My invention comprises an improvement upon the construction disclosed in said patent, particularly as regards the shape and mounting of the heat exchange tubes, and the construction of the furnace base. In accordance with the present invention, I provide a furnace of the general type of that shown in the patent with a plurality of one-piece heat exchange tubes bent to a smooth curve substantially throughout their length. This construction eliminates joints in 10 the heat exchange tube, permits them to be fabricated of welded tubes and makes it possible to install them by inserting one end inwardly through a suitable opening in the side wall of the furnace and outwardly through another opening, by moving the tubes therethrough in 15 one direction only.

The above invention also contemplates an improved form of baffle for the heat exchange tubes, to increase the heating efficiency, as disclosed in 20 a copending application Ser. No. 49,078 of Wilson and Corns.

Another novel feature of the invention is the provision in the furnace base of a layer of refractory units such as brick or block, laid dry, or without mortar, on a suitable supporting framework. A charge supporting plate is carried above the refractory layer on cross beams embedded therein. This construction avoids warping and distortion of the base which has resulted in previous constructions from the exposure to the heat of the furnace of metal parts 35 rigidly attached to the frame of the base.

A preferred embodiment of the invention is illustrated in the accompanying drawings to 40 which reference is made for a complete understanding thereof. In the drawings:

Figure 1 is a partial transverse sectional view through the cover of a furnace;

Fig. 1A is a vertical section taken through a 45 heat exchange tube isolated from the remainder of the furnace, showing the manner of mounting the baffles therein;

Fig. 1B is a transverse section along the line 1B—1B of Fig. 1A;

Fig. 2 is a view of the furnace cover partly in 50 longitudinal section and partly in side elevation;

Fig. 3 is a plan view of the furnace base;

Fig. 4 is a partial sectional view taken along the line IV—IV of Fig. 3 with parts shown in 55 elevation;

Fig. 5 is a similar view taken along the line V—V of Fig. 3;

Fig. 5A is a longitudinal central section through a curb extending peripherally of the furnace base; 5

Fig. 5B is a transverse sectional view taken along the line 5B—5B of Fig. 5B; line 5A—5A of Fig. 5B indicates the plan of the section shown in Fig. 5B;

Fig. 6 is a plan view of a refractory layer taken 10 along the line VI—VI of Fig. 4; and

Fig. 7 is a similar view showing the cross beams incorporated in the refractory layer taken along the line VII—VII of Fig. 4.

Referring now in detail to the drawings and, 15 for the present, to Figures 1 and 2, particularly, a furnace cover indicated generally at 10 comprises refractory side walls 11, end walls 12, and a roof 13 assembled within a structural framework 14 and a casing 15 of metal plate. The 20 cover is provided with a flange 16 depending on the bottom thereof adapted to enter a sealing channel on a charge supporting base with which the cover cooperates. 25

The side walls of the furnace cover are provided with a plurality of heat exchange tubes 21, although the exact mounting of such tubes 30 may be varied within considerable limits. The heat exchange tubes, as shown in Fig. 1, are bent to a smooth curve substantially throughout their length, only about the upper quarter of the length departing from the curve and extending along a substantially straight line. While I prefer to give the bent portion of the tubes substantially the curvature of a parabola, the exact 35 degree or shape of curvature is not limited to that shown. The tubes 21 extend through close fitting openings in an outer refractory member 18 forming part of the side walls of the cover and through larger openings 19 in an inner refractory layer 20. The members 18 are free to move up and down as the tubes expand and contract. 40

Channels 21 extend along the side walls above and below the emerging upper ends of the tubes 45 21. Each tube is attached near its upper end to a plate 22 adapted to be secured to the channels 21. A sealing and insulating layer 23 is formed around the upper end of each tube, behind the plate 22 being preferably cast in plastic form and allowed to set around the tube 50 adhering permanently thereto.

The lower ends of the tubes 21 float freely because the blocks 18 through which they extend are slidible in the cover wall. The tubes 55

are rigidly anchored only at their upper ends to the plates 22. This permits expansion or contraction of the tubes on heating and cooling thereof, without injury to the refractory lining 5 or other parts of the structure.

A burner 24 is mounted in the lower end of each of the tubes 17. A spark gap lighter 25 is mounted adjacent the end of each burner. The lighter 25 is connected to the secondary winding of a transformer indicated at 26. The construction and system of connections of the spark gap lighters are described more fully and claimed in the copending application of James C. Woodson, Serial No. 58,705, filed January 11, 15 1936 for Electrical ignition system and method for furnaces.

A string of baffles 17a secured together by pins 17b is suspended in each tube 17 by a hook 17c. As explained in copending application Ser. 20 No. 49,078, these baffles increase the heating efficiency of the tubes and cause the greater part 25 of the combustion to take place in the lower portion of the tube.

Fuel is supplied to the burners 24 from a 25 manifold 27 connected to a supply line 28 through a main valve 29. Branch connections 30 including control valves 31 extend downwardly from the manifold 27 to Venturi passages 32, each of which supplies a fuel-air mixture to a pair of burners 24 through flexible connections 33, the air being induced into the Venturi passages by the flow of fuel therethrough.

The manifold 27, the connections 30, valves 31 35 and passages 32 as well as the transformers 26, are enclosed within a compartment 34 formed by channels 35 extending along the side walls of the furnace and a covering panel 36. Holes 37 in the panel 36 admit atmospheric air to the induction ports of the Venturi passages.

The connections 35 are similarly enclosed 40 behind a panel 38 and between channels 35. The enclosure for the connections 33 is gas tight and thus forms a seal preventing leakage of the gaseous atmosphere usually maintained within 45 a furnace cover.

It will be apparent that upon the delivery 50 of a fuel-air mixture to the burners 24 and the application of sufficient voltage to the spark gaps 25, the mixture issuing from the burners 55 will become ignited. Combustion of the fuel takes place as the mixture advances through the tubes 17. The latter are thereby heated to a high temperature and radiate heat to a charge of material enclosed by the cover and resting on the base to be described in greater detail later. After complete combustion, the gases are discharged to the atmosphere through the upper open ends of the tubes 17.

Referring now more particularly to Figs. 3 60 through 7 for a detailed description of the base, the latter, indicated generally at 45, includes a frame composed of longitudinal beams 46 connected by transverse beams 47. A bottom plate 48 overlies the frame and has an upstanding peripheral wall 49. A similar wall 50 is spaced inwardly of the wall 49, the two together providing a sealing channel extending around the edge of the base.

A row of blocks 51 of a relatively strong, yet 70 lightweight material such as "haydite" extends around the base within the wall 50, the latter being reinforced by gussets 52. Within the row of blocks 51 is a curb 53 composed of refractory blocks disposed side by side. The curb 53 75 is provided at intervals with bumper plates 54,

to protect the curb against injury by the lower edge of the furnace cover shown in Figures 1 and 2, as the latter is lowered into a position such that it rests on the cover supporting shoulder formed by the row of blocks 51.

As shown in Figs. 5A and 5B, the bumper plates 54 have integral ribs 54a. As the curb is constructed the ribs of the bumpers are inserted between notched out portions of adjacent curb blocks and secured in position by pins 54b. 10 The inner ends of the bumpers overhang the outer flange 59 of the inner sealing channel as shown at 54c. This construction locks the bumpers to the curb and prevents inward warping of the outer flange of the sealing channel.

Within the curb 53, a row of refractory blocks 55 extends around the base. The space within the row of blocks 55 is filled with hollow tile indicated generally at 56.

On top of the tile 56, a relatively thin block 20 of refractory material 57 is disposed. Similar material is placed under the curb 53 and the blocks 55. A sealing pan 58 rests on the block 57 and the blocks 55 and has spaced walls 59 25 upstanding thereon forming an inner sealing channel. The surface of the sealing pan 58 within the inner wall 59 is covered by a layer of fire brick 60. The refractory layer 60 has longitudinal and transverse expansion joints 61 embedded in the several courses thereof.

Cross beams 62 rest on the refractory layer 60. The spaces between adjacent beams are filled with refractory bricks 63. The bricks indicated at 60 and 63 are laid dry and are held in position by the inner wall 59 of the inner sealing channel. Straps 64 extend between the ends of adjacent cross-beams and are secured thereto, to hold the bricks 63 between the cross-beams.

A charge supporting plate 65 rests on the cross-beams. When a charge of material such as sheets, to be annealed, is placed on the plate 65, the load is carried by the cross-beams and the brick therebetween, to the refractory layer 60, the hollow tile 56 and thence to the frame of the base comprising the beams 46 and 47 which rest on any suitable foundation.

Inlet pipes 66 extend inwardly of the ends of the base and upwardly through the refractory layers thereof, for supplying a gaseous atmosphere of any desired character to the space within the cover. A thermocouple pipe 67 similarly extends inwardly from the sides of the base.

In the construction just described, the refractory layers 60 and 63 constitute a charge-supporting pier, the metal parts of which, viz., the beams 62 and the plate 65, are relatively free as regards the remainder of the metallic structure of the base such as the frame composed of beams 46 and 47. As a result, the expansion or contraction of the metal parts exposed to the furnace heat does not cause distortion or warping of the base. The bricks of which the refractory layers are formed are free to move individually and thus provide a further safeguard against warping. The sealing pan 58 prevents the escape of the furnace atmosphere through the refractory bricks which are not absolutely impervious thereto and during cooling prevents atmospheric air and moisture from passing through the refractory into the space 70 under the inner cover. The infiltration of moisture or atmospheric air carrying moisture through the refractory interferes with securing the desired bright annealing. By the use of the sealing plate which extends continuously under 75

the pier and which has a sealing channel formed at its outer edge, there is no possibility of the infiltration of moisture or moisture-laden air through the refractory during the time when 5 the charge is cooling. The portions of the base subject to the furnace heat are thoroughly insulated from the other parts of the base so that excessive heat loss through the base is avoided. The walls of the inner sealing channel 10 59 are rigidly supported between the bricks forming the charge pier and the curb and the bumpers 54 guide the inner cover usually placed over the charge into position with its lower edge penetrating the sealing material disposed in the 15 channel. The inner wall of the channel also maintains the bricks of refractory layer 60 in position.

The advantages of the heat exchange tube shown in Figs. 1 and 2 have already been 20 hinted at. They include a reduction in cost as compared with earlier types of heat exchange tubes employing elbows which required welding in the cover and careful bricking up around them. The curved tube and the manner of suspending it described herein greatly facilitates 25 changing or renewing tubes so that this operation can be performed without shutting down the furnace any material length of time. The free floating lower end eliminates the setting up 30 of any stresses as a result of expansion or contraction of the tubes.

Although I have described and illustrated herein but one preferred form of construction of a furnace cover and base, it will be obvious 35 that changes in the construction shown may be made without departing from the spirit of the invention or the scope of the appended claims.

I claim:

1. A base for a cover type furnace comprising 40 a structural frame, a bottom plate overlying the frame, a pier composed of a plurality of layers of refractory units built up on said plate, a sealing pan between certain of said layers, sealing channels extending peripherally of said pan and plate, and a curb between said channels.

45 2. The combination with a base for cooperation with a cover type furnace, of a peripheral curb upstanding from said base, and bumpers spaced along said curb having portions extending thereto and secured thereto.

50 3. The combination with a base for cooperation with a cover type furnace, of a peripheral curb upstanding from said base, a sealing channel inside of said curb comprising inner and outer flanges, and bumpers spaced along the curb, the inner ends of the bumpers overhanging the outer flange of said channel.

55 4. A base for a cover type furnace comprising a frame, a refractory hearth built up on said frame, a sealing pan on the hearth comprising a metallic plate and a channel formed around the outside of said plate and being contiguous with the plate, the edge of the plate forming the bottom of the channel, a refractory pier on said pan inside the channel, and a refractory curb on the hearth adjacent to and around the exterior of the channel serving to protect said channel and restrain the pan against lateral movement.

5 5. A furnace comprising a hearth and a cover having side walls and a roof, a burner tube having a gradually curved intermediate portion merging directly into upper and lower terminal portions, the burner tube having the curved intermediate portion inside the furnace and having the end portions passing through a side wall of the furnace at an obtuse angle to each other, the tube being disposed in a vertical plane and having a burner at the lower terminal portion 10 thereof, the lower terminal portion being inclined inwardly and upwardly.

15 6. A furnace comprising a hearth and a covering having side walls and a roof, means for heating material disposed in the furnace comprising a plurality of tubes disposed in a vertical plane, the tubes having a curved intermediate portion inside the furnace, which intermediate portion merges directly into upper and lower terminal portions, the terminal portions of the 20 tube passing through the side walls of the furnace at an obtuse angle to each other, the tubes being provided at their lower ends with a burner, the intermediate portion and the lower terminal portion of the tubes describing a parabola. 25

7. The furnace defined by claim 6 characterized by said tube being suspended at its upper terminal portion, the lower end of the tube being free-floating.

30 8. A base for a cover type furnace, comprising a structural frame, a bottom plate overlying the frame, a pier composed of layers of refractory material built up on said plate, a charge supporting plate resting on the upper layer, a sealing pan in said pier, the edges of said pan 35 projecting outwardly of the edges of the layers thereabove, and means including a refractory curb extending around the pier but spaced therefrom to provide a sealing channel along said pan edges.

40 9. A base for a cover type furnace comprising a frame, a refractory hearth built up on said frame, a sealing pan on the hearth having a refractory pier thereon, the pan projecting beyond the pier, a sealing channel extending 45 around the edge of said pan, and means including a refractory curb extending around the outer edge of the pan and spaced from said pier, forming the outer wall of said channel.

50 10. The base defined by claim 9 characterized by a second sealing channel extending about the periphery of the base, said refractory curb being between the two channels adjacent to and around the exterior of the first channel and providing a protection therefor.

55 11. A base for a cover type furnace comprising a frame, a refractory hearth built up on said frame, a sealing pan on the hearth, a charge-supporting pier on the pan, said pan comprising a metallic plate, and means including a refractory curb along the edges of the plate and spaced from said pier, defining a channel around the outside of said plate, the edges of said plate extending beyond the inner wall of the channel sufficiently to form a barrier against 60 infiltration of air through the hearth.

JAMES C. WOODSON.
